UNITED STATES PATENT OFFICE.

JAMES F. WINCHELL, OF SPRINGFIELD, OHIO, ASSIGNOR TO KATE J. POTTER AND JOSEPH E. HEFFELFINGER, OF SAME PLACE, AND ALBERT C. RAMSEY, OF KENTON, OHIO.

GRAVE-VAULT.

SPECIFICATION forming part of Letters Patent No. 242,404, dated May 31, 1881.

Application filed March 29, 1881. (No model.)

To all whom it may concern:

Be it known that I, JAMES F. WINCHELL, a citizen of the United States, resident at Springfield, in the county of Clarke and State of Ohio, 5 have invented certain new and useful Improvements in Grave-Vaults; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 is a representation of a longitudinal section, and Fig. 2 is a perspective detail.

This invention relates to improvements in devices for protecting graves.

The invention consists in the combination of the bottom, having the spring-catches, with 20 the cover, having the movable catch-plates of peculiar form, as set forth and claimed.

In the annexed drawings, A is the base of the protector, which is made by rolling out the sheet metal, at the same time turning up the edges 25 a in finishing.

In putting up the device for use, kerfs are made, ends B turned up, and the laps b riveted down. This forms a simple bottom all in one piece.

30 C C are spring-catches, securely riveted to the bottom inside the turned-up sides and ends, as shown, there being a space between said turned-up edges and the heads c c turned outward.

35 D are guide-pins, firmly fastened in the corners of the bottom, a space being between them and the sides and ends. The tops of these pins are curved inward on the diagonal lines of the bottom, as shown.

40 E is the cover, made of a middle sheet, e, running lengthwise and curved transversely, and the ends e'. These are firmly secured together by riveting or otherwise, the whole thus being in one piece. The exterior width and 45 length of this cover are the same as those of

the interior of the bottom, so that the cover fits snugly inside the latter.

F are catch-plates, made wedge-shaped, and having the ears f, one provided with a perforation, f', the other with a slot, f'', opening 50 toward the edge of the wedge.

Secured to the sides and ends of the cover, and projecting inward, are screw-threaded bolts G, arranged in pairs, the pairs corresponding in number with the spring-catches on 55 the bottom, and located so that when the catch-plates are in place and the cover put on the catch-plates and spring-catches will come together. The catches are held in place by passing one of the bolts G through the perforated 60 ear f, and the slotted ear is slipped over the other bolt of the pair and nuts screwed on the ends of the bolts.

In packing, the nuts are loosened and the slotted ear swung from its bolt and the plates 65 turned on the other bolt. In this way, when the parts are put together, the spring-catches have nothing to engage and the device can be readily separated for use.

In using the device, the catch-plates are 70 swung to place, the nuts tightened, and the cover slipped in place, the guide-pins facilitating the operation. The edge of the cover comes snug within that of the bottom and the spring-catches snap over the plates. 75

To better put on the cover, eyes or handles H are attached to outside thereof.

I claim—

The combination of bottom A, having the spring-catches C C, with the cover E, having 80 the wedge-shaped catch-plates F, hinged at one side and removably held at the other, as set forth.

In testimony whereof I affix my signature in presence of two witnesses.

JAMES F. WINCHELL.
